UNITED STATES PATENT OFFICE.

JOHN McE. AMES, OF NEW YORK, N. Y., ASSIGNOR TO AMERICAN CAR & FOUNDRY COMPANY, OF ST. LOUIS, MISSOURI, A CORPORATION OF NEW JERSEY.

TANK-CAR.

No. 857,571.

Specification of Letters Patent.

Patented June 25, 1907.

Application filed December 28, 1906. Serial No. 349,878.

To all whom it may concern:

Be it known that I, JOHN McE. AMES, a citizen of the United States, residing at the city, county, and State of New York, have 5 invented a certain new and useful Improvement in Tank-Cars, of which the following is a full, clear, and exact description, such as will enable others skilled in the art to which it appertains to make and use the same, reference being had to the accompanying drawings, forming part of this specification, in which—

Figure 1 is a side elevational view, partly in vertical section, of my improved tank car; 15 Fig. 2 is a sectional view taken on the line 2—2 of Fig. 1; Fig. 3 is a plan view of a portion of the underframe; Fig. 4 illustrates a modified form of interlocking members between the tank and underframe; and Figs. 5 20 and 6 illustrate a further modification.

This invention relates to new and useful improvements in tank cars.

The usual practice in tank car construction is to mount the tank on an underframe, and 25 to prevent the tank from rolling bands, which extend over the tank, are secured to the underframe. To prevent the tank from shifting longitudinally, head blocks which serve as abutments for the ends of the tank are 30 usually secured to the underframe.

In the preferred form of my invention the tank is tied to an underframe by means of bands in the usual manner. The head blocks are replaced by lugs secured to the under- 35 frame near the center of the car, which lugs serve as abutments for a projection carried by the tank. The advantage of this construction is that the tank is free to expand and contract independently of the under- 40 frame, as it is not connected by rivets or similar fastening devices, to the underframe.

Referring to the drawings, the underframe comprises body bolsters located near the ends of the car and secured to longitudinal sills. 45 Buffer blocks 2 riveted to the ends of the longitudinal sills are adapted to receive suitable drawbars.

The body bolsters herein shown are built up of flanged diaphragms 3 which extend outwardly from the longitudinal sills, said diaphragms being connected by a channel 4 arranged above the longitudinal sills and a plate 5 below said sills. Center bearings 6

are secured to the under side of the body bolsters, and filler blocks 7 are interposed between the longitudinal sills above the center bearings. The tank rests on wood blocks 8, which blocks are secured to the curved top portion of the body bolsters.

Bands 9 are secured to the body bolsters 60 and extend over the tank. Straps 10 extend under the longitudinal sills and are connected by turn-buckles 11 to tank bands 12 and 12^a, the bands 12^a being connected to curved rods 13 which surround the tank dome 14.

Brackets 15 are preferably secured to the tank bands and support a running board 16 and a hand rail 17. A ladder 18 is secured to the running board.

Flanged plates 19 are secured to the under- 70 frame, preferably near the center of the car. A casting or pressed metal member 20 is secured to the tank and extends downwardly between the flanges of the plates 19. The member 20 is preferably provided with 75 curved flanges which are riveted to the tank, the rivets passing through a plate 21 located inside of the tank. The plate 21 reinforces the tank structure at this point and reduces the liability of leakage.

From the foregoing it will be understood that the member 20 which projects from the tank is held in interlocking engagement with the flanged plates 19 by means of the tank bands. However, any suitable connections 85 between the tank and underframe may be employed in lieu of the tank bands as the same form no part of my invention.

Fig. 4 illustrates a modification in which a casting provided with a recess 22 in its upper 90 face is secured to the underframe, and one of the tank sheets is pressed out to form a projection 20^a, which projection is located in the recess 22.

In the modification shown in Figs. 5 and 6, 95 a casting or pressed metal member 20^b is riveted to the bottom of the tank and rests on the longitudinal sills. A portion of the member 20^b extends downwardly between lugs 19^a which are riveted to the inside of 100 longitudinal sills 1^a. Various other modifications may be made from the design herein shown; for example, a cross bearer could be secured to the longitudinal sills and lugs carried by the tank located on each side of said 105 cross bearer.

I am aware that minor changes in the construction, arrangement and combination of the several parts of my device can be made and substituted for those herein shown and described without in the least departing from the spirit of my invention.

Having thus described the invention, what is claimed as new and desired to be secured by Letters Patent is:

10. 1. In a tank car, the combination with a tank, of a frame, and interlocking members forming abutments between the tank and frame, which members are designed at all times to receive end thrusts and allow the tank to expand substantially throughout its length; substantially as described.
20. 2. In a tank car, the combination with an underframe, of a tank mounted on said underframe, and interlocking members forming abutments between the tank and frame, which members are designed at all times to receive end thrusts and allow the tank to expand substantially throughout its length; substantially as described.
30. 3. In a tank car, the combination with a tank, of a frame, and interlocking members at the center of the car which prevent the tank from shifting longitudinally; substantially as described.
35. 4. In a tank car, the combination with an underframe, of a tank mounted on the underframe, and interlocking members at the center of the car which prevent the tank from shifting longitudinally; substantially as described.
40. 5. In a tank car, the combination with an underframe including body bolsters, of a tank supported by the underframe, and interlocking members arranged between the body bolsters, said interlocking members forming abutments which prevent the tank from shifting longitudinally and allow it to expand; substantially as described.
45. 6. In a tank car, the combination with a tank, of an underframe, bands anchored to the underframe and extending over the tank, and interlocking members which prevent the tank from shifting longitudinally and allow it to expand, the relative position of said interlocking members being constant; substantially as described.
55. 7. In a tank car, the combination with a tank, of an underframe, bands anchored to the underframe and extending over the tank, and interlocking members between said tank and frame which prevent the tank from shifting longitudinally, the relative position

of said interlocking members being constant; substantially as described.

8. In a tank car, the combination with a tank, of an underframe, bands anchored to the underframe and extending over the tank, and interlocking members at the center of the car which prevent the tank from shifting longitudinally; substantially as described. 65

9. In a tank car, the combination with a tank, of a frame, lugs secured to said tank and frame near the center of the car, which lugs interlock and prevent the tank from shifting longitudinally; substantially as described. 70

10. In a tank car, the combination with a tank, of an underframe, lugs secured to the underframe near the center of the car, and a projection carried by the tank arranged between said lugs; substantially as described. 75

11. In a tank car, the combination with a tank, of an underframe, lugs secured to the underframe near the center of the car, and a projection carried by the tank arranged between said lugs; substantially as described. 80

12. In a tank car, the combination with a tank, of a frame including body bolsters, a tank-supporting member near the center of the car, and lugs co-operating with said tank-supporting member to prevent the tank from shifting longitudinally; substantially as described.

13. In a tank car, the combination of a tank, an underframe, and interlocking members on said tank and underframe, said members being located at the center of the car and having coincident engaging faces; substantially as described. 90

14. In a tank car, the combination with a tank, of a frame, interlocking members between said tank and frame, one of which interlocking members is riveted to the tank near the center thereof, the rivets passing through a reinforcing plate located inside of the tank; substantially as described. 95

15. In a tank car, the combination with a tank, of an underframe, and interlocking members between said tank and underframe, one of which interlocking members is secured to the underframe near the center thereof, substantially as described. 100

In testimony whereof I hereunto affix my signature in the presence of two witnesses, this 21st day of December, 1906.

JOHN McE. AMES.
